BRAUN TUBE

Kurt Schlesinger, Berlin, Germany, assignor to
 Radioaktiengesellschaft D. S. Loewe, Berlin-
 Steglitz, Germany

Application September 28, 1934, Serial No. 745,952
 In Germany October 2, 1933

3 Claims. (Cl. 250—162)

The invention relates to a Braun tube, more particularly for television purposes, in which merely comparatively low potentials are required for deflection of the ray, and means are provided 5 in order to make the form and size of the image point constant and independent of its intensity and of its position on the image screen.

It has already been proposed in one of the earlier applications of the applicant to concentrate the controlled electronic ray proceeding 10 from the cathode on to a diaphragm, and to reproduce this diaphragm on the image screen by means of a suitable electron-optical system. In this arrangement the deflecting system is situated 15 between the electron-optical system and the fluorescent screen.

It has also already been proposed to employ a so-called "electron-gun", and to obtain the concentration by means of a field, which is produced 20 by means of a metallic coating on the bulb of the tube linked up with high potential.

In this arrangement the concentration is effected by field lines filling the entire space between the fluorescent screen and the electron 25 gun.

The deflecting systems in this arrangement are situated within the concentration field itself, so that the distribution of the field in the vicinity of the first deflecting system is different 30 from that in the vicinity of the second deflecting system. In consequence it is impossible with these arrangements to operate with electrostatic deflecting systems.

These known arrangements do not permit of 35 the production of television images, which possess an even structure over their entire surface.

The object of the invention is a Braun tube which allows of the production of completely regular images.

40 According to the invention:

1. The controlled electronic ray is preliminarily concentrated onto a diaphragm,

2. The diaphragm is reproduced on the image screen by means of an electron-optical system, 45 which acts preferably as a relatively thin collecting lens (of, for example, 3 cm. in thickness),

3. The deflection necessary for producing the line screen is performed prior to entry of the cathode ray into the lens, preferably in a completely fieldless space,

4. The deflection is preferably performed by a system, which causes both deflections in the same plane, for example according to the patent application Ser. No. 726,477, filed May 19, 55 1934.

5. A substantially fieldless space is provided between the electron-optical system and the fluorescent screen.

The simultaneous use of all of the stated measures is particularly convenient; the single measures, however, are also of particular importance per se, and may also be employed singly or in partial combination.

A form of embodiment of the tube according to the invention is illustrated by way of example 10 in the drawing, in which

Fig. 1 shows a possible total arrangement of the tube, while in

Fig. 2 there is shown a particular form of embodiment of the preliminary concentration 15 system, and in

Fig. 3 a form of embodiment of the deflecting system.

Figs. 4 and 5 show particular forms of embodiment of the lens according to the invention. 20

In Fig. 1:

1 is the bulb of the tube, which consists of the neck portion 2 and the preferably spherical envelope portion 3. The fluorescent screen 4 may either be suspended in the bulb, or constructed 25 inside the form of a fluorescent layer 5 applied in direct fashion to the wall of the bulb. The electrons proceeding from the cathode 6, which conveniently is constructed in the form of an indirectly heated large surface cathode having an 30 emissive layer sunk into the surface, are preliminarily concentrated on to the diaphragm 10 by means of a system consisting, for example, of the cylinder 7 and the preliminary anode 8 and an additional cylinder 9. In this connection the 35 cylinder 7 may possess a weakly negative bias, the preliminary anode 8 and the diaphragm 10 may be raised to a weak positive potential (for example +300 volts), and the potential of the cylinder 9 be weakly negative (for example 40 +200 volts) in relation to the diaphragm 8.

The control takes place by applying the control alternating potential to the control plate 11 arranged in the cylinder 7 preferably at a distance from the cathode 6 corresponding to the 45 cathodic dark space with usual gas pressures and preferably in conductive connection with the cylinder. Preferably the system may be adjusted in such fashion that the electronic ray at its maximum intensity passes through the preferably 50 small aperture 12 (for example 1 mm.²) of the diaphragm 10 without being partly stopped by said diaphragm 12 (for example 1 mm.²) of the diaphragm 10.

The diaphragm aperture 12 is reproduced on 55

the fluorescent screen by means of the electron-optical system comprising the perforated plate 13 and the annular collar 14. The spacing between the diaphragm to be reproduced and the lens (object spacing) on the one hand and between the lens and the fluorescent screen on the other hand may preferably be so selected (for example in the ratio of 2:1) that the diaphragm is reproduced on the image screen on reduced scale (for example 1:2). For example, the object spacing may be selected at 300 and the image spacing at 150 mm.

The annular plate 13, which is connected with a low positive potential—preferably the same potential as the diaphragm 10—has at the same time the object of screening off the alternating field of the deflecting plates against the lens.

The deflecting system 17, 18, the aperture of which directed towards the plate 13 is preferably—either by inclined or by parabolic construction of the deflecting elements—made larger than the inlet aperture, may conveniently be disposed as close as possible to the plate 13, for example at a distance of very few millimeters from the same.

As already set forth, the deflecting system is situated in the entirely fieldless space between the electrodes 10 and 13. The space between these electrodes may be screened off towards the outside by means of a metallic tube connecting the electrodes or also by a metallic coating on the neck of the tube having a corresponding length and being raised to the same potential as the electrodes 10 and 13.

The second electrode of the electron-optical system, the annular plate 14, is preferably constructed, according to the invention, as a narrow or very narrow ring fitting closely against the wall of the bulb. A part of the wall of the bulb between this electrode and the fluorescent screen is furnished with a metallic coating, which is conductively connected with the electrode 14, and in consequence possesses the same potential as this electrode (for example 2000 volts).

Since the wall of the bulb greatly recedes immediately behind the electrode, the relatively weak field formed between the electrode 14 and the fluorescent screen does not appreciably participate in the optical effect of the system.

The metallic coating of the bulb in substance produces the effect that the wall charges are neutralised and deformations in the shape of the image caused by the same avoided.

Instead of connecting the metallic coating with the electrode 14 it is sometimes convenient to impart to the same a potential which is weakly negative (for example to the extent of 100–300 volts) in relation to the electrode 14.

In place of the preliminary concentration system illustrated in Fig. 1, it is also possible, for example, to employ this system shown in Fig. 2. In the figure:

6 is the cathode, 7 the cylinder constructed as described in Fig. 1 with the control plate 11, 8 a preliminary anode, and 10 the diaphragm with the aperture 12. The system is adjusted in such fashion by suitable selection of the potentials that the cathode ray in the case of its maximum intensity passes through the aperture 12 without being partly stopped by the diaphragm 10.

In this form of embodiment it is particularly important to select correctly the sizes and also the spacing of the different elements.

If the Wehnelt cylinder 7 is to be operated with a very weak negative bias (for example in

the “light” condition: zero), and a weak positive potential of, for example, +300 volts is applied to the preliminary anode 8, the diameter of the cylinder 7 may be selected at 10 mm., the distance of the plate 11 from the cylinder edge (the extent of introduction) at 1.5 mm., and the distance of the cylinder 7 from the plate 8 at 2 mm.

In the Braun tubes hitherto known the deflecting systems are arranged in axial consecution, at a relatively large distance apart.

It is absolutely essential in the case of these arrangements to dispose the systems at a comparatively large distance apart, as otherwise a mutual interference effect of the deflecting fields takes place, which effect results in distortion and curvature of the image.

This known arrangement of the deflecting systems in axial consecution, however, results in the fact that the spacing of the pivot point of the ray in the two deflecting directions from the lens is of different amount, so that the conditions under which the ray passes the lens are not the same in respect of the two directions of deflection, and that further the lens requires to possess a very large aperture.

According, therefore, to the invention, there is conveniently employed for deflecting purposes a system according to the patent application Ser. No. 726,477, filed May 19, 1934 which enables the deflection to be performed in both directions in the same plane without any mutual interference of the deflecting fields.

According to the invention, the line frequency deflection takes place by the use of an electrostatic field, whilst for frame frequency deflection purposes there is employed an electro-magnetic field. The elements acting as static deflecting plates are then conveniently constructed themselves as pole shoes for the magnets causing the frame frequency deflection. These plates, in accordance with the invention, may also conveniently be tilted in relation to each other, or constructed in curved form.

A form of embodiment of the deflecting system according to the invention is illustrated by way of example in Fig. 3.

In the same:

2 is the neck of the tube, and 17 and 18 are the deflecting elements, which are supplied which on the one hand, in the manner known per se, with the potentials necessary for electrostatic deflection, and which at the same time are constructed as pole shoes for the magnets 19 and 20 causing the frame frequency deflection. The elements 17 and 18 are preferably constructed in such fashion that the same extend as closely as possible towards the wall of the tube. The tube 16 connecting the diaphragms 10 and 13 (cf. Fig. 1) may in this case conveniently be furnished with recesses, through which the elements 17 and 18 project.

Various forms of embodiment of an electron lens may be employed in place of that set forth in Fig. 1. Thus, for example, it is possible to furnish the glass bulb 1 at that particular point at which the lens is to be mounted with two metallic annular coatings insulated one against the other, of which coatings the one is connected with a weak and the other with a strong positive potential.

The refractive power of the lens is determined in this case inter alia by the spacing between the two annular coatings, and may be adjusted as desired by variation of this spacing.

It is also convenient in the case of this embodiment to

ment to screen off the deflecting systems against the lens field by means of a diaphragm, which conveniently may be connected with the potential of the weakly positive coating.

5 A form of embodiment of a lens of this nature is illustrated by way of example in Fig. 4. In the same:

10 1 is the glass envelope, 17 and 18 are the deflecting elements, and 13 is the screening diaphragm. On the glass wall itself there are provided the two coatings 21 and 15. The coating 21 is supplied with a weak positive potential (for example 300 volts) and the coating 15 with the anode potential (for example 2000 volts).

15 13 In order to prevent the ray from being appreciably further influenced in the space between the electron lens and the fluorescent screen there is conveniently provided a diaphragm 14, which may consist of a narrow annular collar, and 20 preferably be conductively connected with the metallic coating 15. The diaphragm 14, in accordance with the invention, may also be replaced by a small metallic tube 22, which extends for a short distance, for example 5 mm.-3 cm. 25 into the interior of the bulb (Fig. 5).

It is also possible to employ in lieu of the forms of lens as described electron-optical systems of other types.

30 It is convenient according to the invention, particularly at those points at which there is situated the inner coating connected with a low positive potential, to furnish at the same time the outside with a metallic coating, and to connect this outer coating with earth.

35 35 According to a further feature of the invention two pairs of deflecting plates arranged in axial consecution in the described field-free space may be used. For this purpose each of the systems is arranged strictly symmetrically with respect to the electronic lenses and to the tube axis and one plate of each pair is supplied with the respective deflecting voltage, while the other plate is supplied with a voltage of the same amplitude but reverse phase.

40 45 The necessary voltage of reverse phase may be easily produced with the use of a phase reverse valve controlled by the output voltage of one of the well known relaxation oscillation generators, said valve having a potentiometer arranged in its output circuit, the desired reverse phase voltage being tapped at said potentiometer so as to have the same potential as the original deflecting voltage.

Deflecting systems of this kind have been found 50 to have no disturbing effect neither upon each other nor upon the field of the electric lens.

I claim:

1. A Braun tube for television purposes comprising an evacuated envelope enclosing a 55 cathode, a modulating grid mounted in the vicin-

ity of said cathode, a plate having an aperture, said plate being mounted in the vicinity of said grid, a picture receiving screen, an electrostatical electron-optical system mounted between said plate and said screen for reproducing said aperture on said screen, one pair of deflecting coils for deflecting the cathode ray in one direction, and one pair of deflecting plates for deflecting the cathode ray in a direction perpendicular to the first said one, said deflecting plates and said 10 deflecting coils being mounted along the same axis, said deflecting plates being mounted between said plate and said electron-optical system in close proximity to said system, the distance between said electron-optical system and said 15 plate having said aperture being at least as great as the distance between said system and said screen.

2. A Braun tube for television purposes comprising an evacuated envelope enclosing a cathode, a modulating grid mounted in the vicinity of said cathode, a plate having an aperture, said plate being mounted in the vicinity of said grid, a picture receiving screen, an electrostatical electron-optical system mounted between said 20 plate and said screen for reproducing said aperture on said screen, said electron-optical system comprising two electrodes, each of said electrodes comprising a cylinder having an apertured plate mounted therein and having an open cylindrical 25 portion protruding beyond this apertured plate in the direction towards the other one of said electrodes, the two cylinders being adapted to have different constant potentials impressed 30 thereon, and deflecting means for deflecting the 35 cathode ray in two directions perpendicular to each other.

3. A Braun tube for television purposes comprising an evacuated envelope enclosing a cathode, a modulating grid mounted in the vicinity 40 of said cathode, a plate having an aperture, said plate being mounted in the vicinity of said grid, a picture receiving screen, an electrostatical electron-optical system mounted between said plate and said screen for reproducing said aperture on 45 said screen, said electron-optical system comprising two electrodes, each of said electrodes comprising a cylinder having an apertured plate mounted therein, the diameters of said cylinders 50 being equal, the diameters of the apertures of the plates inserted in said cylinders being different from one another, said two cylinders being coaxially arranged and being adapted to have different potentials impressed thereon, and deflecting means for deflecting the cathode ray in 55 two directions perpendicular to each other for scanning said picture receiving screen.
